United States Patent Office

Des. 223,648
Patented May 16, 1972

223,648

BEVERAGE DISPENSER OR SIMILAR ARTICLE

Robert B. Hartley, Columbia Heights, Minn., assignor to
The Cornelius Company, Anoka, Minn.

Filed Nov. 9, 1970, Ser. No. 25,903

Term of patent 14 years

Int. Cl. D15—08

U.S. Cl. D94—3

FIG. 1 is a front perspective view of a beverage dispenser showing my new design, the side opposite that shown being a mirror image of the side shown; and

FIG. 2 is a front elevational view thereof.

The rear is plain and unornamented.

I claim:

The ornamental design for a beverage dispenser or similar article, substantially as shown and described.
